UNITED STATES PATENT OFFICE

2,099,698

HEEL-SEAT FITTING MACHINE

Ralph S. Megathlin, Wollaston, Mass., assignor to
 United Shoe Machinery Corporation, Paterson, N. J., a corporation of New Jersey

Application August 15, 1935, Serial No. 36,345

8 Claims. (Cl. 12—31.5)

This invention relates to the manufacture of shoes and is illustrated as embodied in a heel-seat fitting machine.

In United States Letters Patent No. 2,072,900, granted March 9, 1937, in my name, there is disclosed a shoe having a sole provided with a pair of heel-breast receiving shoulders, the inner portions of which are substantially complementary to portions of the breast of a Cuban heel to be attached to the shoe and the outer or edge portions of which project rearwardly of the sole from the inner portions. Preparatory to attaching the heel to the shoe the breast corners of the heel are forced forwardly of the shoe against the rearwardly projecting outer portions of the heel-breast receiving shoulders to cause such portions to be forced or bent forwardly so that the breast of the heel engages the complementary inner portions of the heel-breast receiving shoulders.

With the above construction permanently closed joints are formed between the breast corners of the heel and the heel-breast receiving shoulders, the edges of the sole at the rear end of the shank being effectively supported by the heel against drooping away from the shoe upper.

To facilitate the cutting of such heel-breast receiving shoulders, and in accordance with a feature of this invention, the illustrated heel-seat fitting machine is provided with a pair of knives movable in paths disposed at substantial angles to the general plane of the sole of a shoe supported in the machine, and shaped to form upon the sole a pair of heel-breast receiving shoulders of the character above described.

These shoulder-forming knives are illustrated as embodied in a heel-seat fitting machine of the type disclosed in United States Letters Patent No. 2,053,295, granted September 8, 1936, on an application filed in the name of Fred L. MacKenzie.

When reducing the heel-seat portions of soles attached to shoes by means of machines of the general type disclosed in the above-mentioned United States Letters Patent No. 2,053,295 it occasionally happens that one or more of the lasting tacks at the heel seat are not properly driven into the overlasted counter portion of the shoe upper and therefore extend across the path of movement of the heel-seat reducing knife of the machine thereby nicking the cutting edge of the knife as it moves forwardly to reduce the heel-seat portion of the sole. With the above considerations in view and in accordance with another feature of this invention the illustrated machine is provided with a shoe positioning gage

for moving the shoe upper transversely of the path of movement of the heel-seat reducing knife, thus insuring that improperly driven lasting tacks will not be engaged by the knife.

These and other features of the invention will be described as embodied in an illustrated machine and pointed out in the appended claims.

In the drawings,

Fig. 1 is a perspective view partly in section, of portions of a heel-seat fitting machine embodying the present invention;

Figs. 2, 3 and 4 are perspective views showing an improved knife for forming heel-breast receiving shoulders such as above described;

Fig. 5 is a plan view of a work-positioning portion of the machine;

Figs. 6, 7 and 8 are vertical sections showing a portion of the machine with work presented thereto during three successive stages of the heel-seat fitting operation;

Fig. 9 is a perspective view of the heel end of an inverted shoe which has been operated upon by the illustrated machine;

Fig. 10 is a detail plan view partly in section, on an enlarged scale, showing a heel being forced into its proper position upon the sole of the shoe preparatory to attaching the heel to the shoe; and

Fig. 11 is a perspective view of the rear end of an inverted shoe after the heel has been attached thereto but before the edges of the sole of the shoe have been trimmed flush with the sides of the heel.

The illustrated machine is described with reference to forming heel-breast receiving shoulders 20 (Figs. 9 and 10) and reducing the heel-seat portion 22 (Fig. 9) of a sole 24 which is attached to a shoe 26. Such a heel-seat construction is disclosed and claimed in the above-mentioned United States Letters Patent No. 2,072,900. The heel-breast receiving shoulders 20 comprise inner portions or faces 28 which are substantially complementary to opposing areas of the breast of a heel 29 (Fig. 11) attached to the shoe, and also comprise reversely curved portions 30 extending rearwardly of the sole 24 and toward corresponding edges 32 of the same. The faces 30, together with extensions 34 of the heel-breast receiving shoulders 20, form projections 36 at the outer ends of the shoulders.

Preparatory to attaching the heel 29 to the shoe 26 the breast corners of the heel are forced against the faces 30 (Fig. 10) thereby causing the projections 36 to be compressed or forced forwardly and toward the shoe upper so that the 55

breast of the heel engages the inner faces 28 of the heel-breast receiving shoulders 20. With the above construction the edges 32 of the sole 24 are effectively supported by the heel against drooping away from the shoe upper.

As the heel 29 is moved forwardly of the sole the projections 36 are forced toward the shoe upper as above described since the breast 40 of the heel forms an acute angle with the shank portion 10 of the sole 24. The projections 36 of the sole 24 are readily compressed under forward pressure of the heel 29 as the heel is moved forward into contact with inner portions 28 of the shoulders.

The heel-breast receiving shoulders 20 may be 15 quickly and effectively formed by knives 42 which are adjustably secured to a knife carrier 44 (Fig. 1) which is described in detail in the above-mentioned United States Letters Patent No. 2,053,295. The shoulder-forming knives 42 may be adjusted 20 equal distances toward and away from the median plane 46 of the carrier 44 by turning a screw 48.

The heel-seat portion 22 of the sole of the shoe is supported upon a plate 50 constructed and 25 arranged to be positioned within the rand crease of the shoe, the forward part of the shoe being held by the operator. The shoe is positioned widthwise and lengthwise in the machine by centralizing and back gages 52, 54, respectively. The centralizing gage 52 and the back gage 54 are slideable along guideways of the main frame of the machine and are urged under spring pressure to their forward positions shown in Fig. 1 when the shoe is 30 removed from the machine. The shoe is centralized by bifurcations 56 of the centralizing gage 52 as it is forced rearwardly in the machine and forces the back gage 54 into contact with a stop slide 60. The stop slide 60 is moved rearwardly under pressure of the shoe until a depending portion 61 of the slide engages a spiral cam 35 62 (Fig. 1) which is automatically swung to a predetermined position by a heel in a heel gage (not shown). The shoe-positioning mechanism, 40 including mechanism for operatively connecting the heel gage and the spiral cam 62, is described 45 in detail in the above-mentioned United States Letters Patent No. 2,053,295 and therefore need not be more fully described herein.

The crease plate 50 has a U-shaped opening 64 50 (Fig. 1) and a bevel-face 66, the lower edge of which terminates in close proximity to the bottom face of the crease plate 50. The illustrated machine is of the type in which the margin of the heel-seat portion of the sole is distorted with 55 relation to the central part of the heel-seat portion while a knife 68 moves forwardly along the bottom of the face of the crease plate 50 to trim and reduce the heel-seat portion of the sole by a beveling cut thereby providing a beveled margin 70 (Fig. 9).

Prior to forcing the central part of the heel-seat portion of the sole through the opening 64 the margin of the heel-seat portion of the sole 65 is clamped against the bevel-face 66 of the plate 50 by a presser unit 72. The presser unit 72 preferably comprises a plurality of relatively movable parts and is constructed and arranged to clamp the margin of the heel-seat portion of a 70 sole of non-uniform thickness against the plate 50. The presser unit 72 is carried by a housing 74, an extension 76 (Figs. 6 and 7) of which slides within a boss 78 of the machine frame. The presser unit 72 is operated by a treadle (not shown) which is operatively connected to a lever 75

80 (Fig. 6) pivotally connected to a coupling 82 by a link 84. The coupling 82 is in threaded engagement with a rod 86 to the lower end of which a bulger 88 is secured. The presser unit 72 is yieldingly forced against the sole through a spring 90 (Fig. 6) which is enclosed within a casing 92 secured to the rod 86, the upper end of the spring engaging the casing 92 and the lower end of the spring engaging the upper end of the extension 76 of the housing 74. When the treadle is first 10 depressed the presser unit 72 forces the margin of the heel-seat portion of the sole against the bevel-face 66 of the plate 50. Further downward movement of the treadle causes the bulger 88 to force the central part of the heel-seat portion of the sole through the opening 64 and below the bottom face of the plate 50. The sole-engaging face of the bulger 88 in its lowered position (Figs. 7 and 8) is located just above the bottom face of the plate 50 in order to insure that 20 the heel-seat reducing knife 68 which moves forwardly of the sole in a fixed path shall not engage the bulger.

In order to insure that the knives 42 may replace corresponding knives used in the machine 25 disclosed in the above-mentioned United States Letters Patent No. 2,053,295 shanks 94 of the shoulder-forming knives 42 are substantially identical with the shanks of shoulder-forming knives 30 of such machine. In order to form the heel-breast receiving shoulders 20 the shoulder-forming knives 42 are moved in paths disposed at substantial angles to the general plane of the sole. The bulger 88 is moved downwardly with the shoulder-forming knives 42 which have a slight 35 lead over the bulger and form the heel-breast receiving shoulders while the forward end of the heel-seat portion of the sole is substantially flat widthwise. The knives 42 may be referred to as 40 chisel-shaped blades and are provided with cutting edges comprising inner portions 96 which are curved thicknesswise of the blade and form the inner faces 28 of the heel-breast receiving shoulders, the inner faces 28 being substantially 45 complementary to opposing heel breast areas with which they engage. The cutting edges of the knives 42 are also provided with outer portions which comprise reversely curved portions 98 for forming the faces 30, and extensions 100 which, 50 together with the reversely curved portions 98, form the projections 36 at the outer ends of heel-breast receiving shoulders 20. The reversely curved portions 98 of the cutting edges have the general form of a relatively flat ogee curve and 55 extend rearwardly and toward corresponding edges of the sole from the inner portions 96 of the cutting edges. The extensions 100 of the cutting edges of the knives 42 are usually of considerable length to insure that U-shaped chips 60 trimmed from the heel-seat portions of wide soles by the knife 68 shall be completely severed from the soles.

As above stated, the breast corners of the heel are forced forwardly of the shoe against the faces 65 30 (Fig. 10) of the heel-breast receiving shoulders preparatory to attaching the heel 29 to the shoe and compress or force the projections 36 forwardly of and toward the shoe upper so that the breast 40 of the heel engages the inner faces 70 28. The reversely curved portions 98 of the cutting edges of the knives are preferably of sufficient length to accommodate a run of heels without having to adjust the knives 42 toward or away from each other. After the heel 29 has been 75

permanently secured to the shoe 26 the edges 32 of the sole are trimmed along lines 102 (Fig. 11) flush with the sides of the heel. The inner portions 28 of the heel-breast receiving shoulders 20 may be described as extending forwardly of the sole as they approach corresponding edges 32 of the sole, and the reversely curved portions 30 may be said to extend rearwardly of the sole as they approach corresponding edges 10 32 of the sole. The inner and the reversely curved portions 96, 98, respectively, of the cutting edge of the knife 42 may also be described as being humped in opposite directions thicknesswise of the blade, the inner portion 96 being concave 15 forwardly of the sole and the reversely curved portion 98 being concave rearwardly of the sole. The reversely curved portion 98 of each of the cutting edges is angularly disposed with relation to the adjacent end of the inner portion 96 of the 20 cutting edge and forms a salient portion therewith.

Occasionally one or more heel-seat lasting tacks 104 (Fig. 9) of the shoe are not properly driven. These incompletely driven tacks are ordinarily 25 hidden from the view of the operator by the sole and are likely to nick the cutting edge 106 (Fig. 1) of the heel-seat reducing knife 68. In order to insure that improperly driven heel-seat lasting tacks 104 shall not be engaged by the cutting 30 edge 106 of the cutter, the back gage 54 has a shoe-engaging portion 108 which is depressed by the leading bevel-surface 109 of the knife 68 during the heel-seat reducing operation and which swings the rear end of the shoe about the forward end of the crease plate 50 and away from the path of movement of the knife (Figs. 7 and 8). In order to guide the shoe-engaging portion 108 of the back gage 54 in a fixed path disposed at right angles to the path of movement of the heel-seat reducing knife 68, the shoe-engaging portion is provided with a T-shaped extension 110 (Figs. 1 and 5) constructed and arranged to engage within a guideway 111 of the back gage. The shoe-engaging portion 108 of the back gage 45 54 is normally held in a raised position by a spring 112 the upper end of which is secured to a pin 114 and the lower end of which is secured to a pin 116 carried by the shoe-engaging portion 108 of the back gage.

50 In order to perform the heel-seat fitting operation the operator forces the inverted shoe heel-end first against the centralizing and back gages 52 and 54, respectively, to position the heel-seat portion of the sole widthwise and lengthwise upon the plate 50. The operator then depresses the treadle (not shown) thereby lowering the rod 86 to clamp the margin of the heel-seat portion of the sole against the bevel-face 66 of the plate 50 (Fig. 6). Continued depression of the 55 treadle operates the knives 42 which form the heel-breast receiving shoulders 20 and also causes the bulger 88 which is carried by the rod 86 to force the central part of the heel-seat portion of the sole through the opening 62 to the position shown in Fig. 7. The knife 68 is then automatically operated to reduce the heel-seat portion of the sole. As the knife 68 moves forwardly its bevel-face 109 forces the shoe-engaging portion 108 of the back gage 54 downwardly. As 60 the shoe-engaging portion 108 of the back gage is lowered (Figs. 7 and 8) the heel end of the shoe upper is forced away from the path of movement of the knife 68 thereby insuring that un-driven tacks 104 upon the overlasted counter 65 portion of the shoe upper shall not be engaged 70

by the knife. The machine is preferably provided with a one-revolution clutch so that it comes to a stop after returning to starting position.

Having described the invention, what I claim as new and desire to secure by Letters Patent 5 of the United States is:

1. In a heel-seat fitting machine, a support for the sole of a shoe, and chisel-shaped blades movable in paths disposed at substantial angles to the general plane of the sole and constructed and arranged to form heel-breast receiving shoulders upon the sole, each of said blades comprising an elongated curved inner cutting edge extending transversely of the sole and shaped to form an inner shoulder portion which is substantially 15 complementary to an opposing area of the breast of a heel to be attached to the shoe, each of said blades also comprising a short outer cutting edge which is reversely curved thicknesswise of the blade and extends rearwardly of the sole and toward the corresponding edge of the sole from the outer end of the inner cutting edge and is shaped to form an outer shoulder portion which is constructed and arranged to be forced forwardly by the heel so that the heel engages the inner portion of the shoulder. 20

2. In a heel-seat fitting machine, a support for a sole, and knives movable in paths disposed at substantial angles to the general plane of the sole and constructed and arranged to form heel-breast receiving shoulders upon the sole, each of said knives having a continuous cutting edge which comprises inner and outer portions offset lengthwise of the sole from each other and an intermediate portion extending rearwardly of 35 and toward the corresponding edge of the sole from the inner portion of the cutting edge.

3. In a heel-seat fitting machine, a member constructed and arranged to be engaged by a sole, and a pair of chisel-shaped knives which are movable in paths disposed at substantial angles to the general plane of the sole and are constructed and arranged to form heel-breast receiving shoulders upon the sole, each of said knives having a cutting edge comprising an inner curved portion 40 and an outer portion which is offset lengthwise of the sole from the outer end of said inner portion and is joined thereto by a reversely curved portion. 45

4. In a heel-seat fitting machine, a support for 50 a sole, and blades movable in paths disposed at substantial angles to the general plane of the sole and constructed and arranged to form heel-breast receiving shoulders upon the sole, each of said blades being provided with a cutting edge having the general form of an ogee curve.

5. A heel-seat fitting machine having, in combination, a plate having an opening and constructed and arranged to be positioned between the sole and upper of a shoe, means for forcing 60 the central part of the heel-seat portion of the sole through the opening and beyond a face of said plate, a heel-seat reducing knife movable forwardly of the sole along said face of the plate, and a member constructed and arranged to move 65 the shoe upper away from the path of movement of the knife as the knife reduces the heel-seat portion of the sole.

6. In a heel-seat fitting machine, a plate having a U-shaped opening, said plate being constructed and arranged to support the heel-seat portion of a sole attached to a shoe upper, means including a gage constructed and arranged to be engaged by the rear end of the shoe upper for 70 positioning the heel-seat portion of the sole upon 75

the plate, means for forcing the central part of the heel-seat portion of the sole through the opening and beyond a face of the plate, and a heel-seat reducing knife which is in engagement with said face and is movable in a fixed path extending lengthwise of the sole, said gage being mounted for translatory movement in a fixed path disposed at a substantial angle to the path of movement of the knife to force the rear end of the shoe upper away from the path of movement of the knife during the heel-seat reducing operation.

7. A heel-seat fitting machine having, in combination, a crease plate, means for cooperating with the crease plate to distort the heel-seat portion of a sole which is attached to a shoe upper and is supported by the plate, a heel-seat reducing knife movable in a fixed path, and a back gage constructed and arranged to be engaged by the rear end of the shoe upper, said back gage being movable under pressure of the knife to force the shoe upper away from the path of move-

ment of the knife thereby insuring that undriven tacks in the overlasted counter portion of the shoe upper shall not be engaged by the knife during the heel-seat reducing operation.

8. In a heel-seat fitting machine, a member for supporting the heel-seat portion of a sole attached to a shoe upper, means comprising a knife movable in a fixed path and constructed and arranged to reduce the heel-seat portion of the sole for the reception of a heel, and a back gage for positioning the sole lengthwise upon said member, said gage comprising a shoe-engaging portion which is normally positioned in the path of movement of the knife and is constructed and arranged to move the rear end of the shoe away from said path under pressure of the knife thereby insuring that the knife shall not engage undriven tacks in the overlasted counter portion of the shoe upper during the heel-seat reducing operation.

RALPH S. MEGATHLIN.
